DROPPER STOPPER

David A. Woodcock, New York, N. Y., assignor to
 Vick Chemical Company, Philadelphia, Pa., a
 corporation of Delaware

Application January 4, 1935, Serial No. 439

5 Claims. (Cl. 221—148)

This invention relates to a dropper stopper.

It is primarily aimed to provide an improved construction of the general class employing a rigid cap, an elastic bulb and a bottle sealing flange and a dropper tube carried by the latter.

It is usual in the distribution of medicaments intended for application to the nose and throat to sell a bottle of the liquid closed by a screw cap and to furnish with such bottle a combination stopper and dropper for use with the bottle by the person using it, the original screw cap being thrown away and the combination stopper and dropper being subsequently used as both a bottle closure and applicator.

15 A primary object is to provide a form wherein the cap has an interior groove with top and bottom walls into which a bottle-neck sealing flange at the base of the bulb snaps after being temporarily constricted by passage through that

20 part of the cap beneath the groove. I find that this improved construction practically eliminates a relative sliding movement between the elastic part as a whole and the cap, enables a thinner elastic flange to be employed, 25 and insures a more unitary action, especially minimizing the possibility of accidental separation of the assembled parts comprising the device.

More specific objects and advantages will in 30 part be pointed out and otherwise become apparent from the following description taken in connection with the accompanying drawing illustrating an operative improvement embodying said changes.

35 Figure 1 is a view in substantially vertical section showing the device applied to a bottle or container; Figure 2 is a central vertical section through the dropper stopper as removed from the container; Figure 3 is a top or plan view of the device, and Figure 4 is a central vertical section suggesting the method of attaching the elastic body to the cap.

40 Referring specifically to the drawing wherein like reference characters designate like or similar parts, the invention comprises a one piece rubber or other elastic body 10 carrying a dropper tube 11, and which body in turn is carried by a cap 12 adapted to unitarily secure all of said parts to the neck of a bottle or container 13.

45 Said bottle or container 13 may be of glass or any other suitable material and of any preferred form, usually having screw threads 14 about the neck which are engaged by screw threads 15 of said cap 12, which latter is made 50 of any suitable rigid material, usually metal.

Said cap 12 at the upper portion has a top wall 16 provided with a central opening 17, and a lateral wall 18 spaced below and parallel to the top wall 16 so as to form a groove 19. A vertical side wall 20 connects the walls 16 and 18 and is preferably roughened or knurled as shown at 21 to facilitate gripping engagement by the fingers. Such cap 12 may be readily stamped or manufactured in a single metallic piece.

5 Reverting to the elastic body 10, it comprises 10 a bulb 22 extending through the opening 17, and a lateral flange 23 extending outwardly from the bulb at the base thereof, into the groove 19 and snugly fitting the same. Said flange 23 is extended inwardly at 24 at the entrance to the bulb 15 22 and portion 24 snaps into an annular groove 25 adjacent the top of the dropper tube 11, which latter may be made of any desired rigid material, for instance, glass.

Particular attention is directed to the fact that 20 the flange 23 is of greater diameter than the entrance to the groove 19 or portion of the cap having the screw threads 15, to the end, as shown in Figure 4, that the flange 23 will be constricted and contracted while it is applied to the cap. 25 Such contraction or constriction causes the flange 23, when alined with the groove 19, to somewhat forcibly snap into the groove 19 and occupy the same. Thereafter the marginal part of the lower surface of the flange 23 rests upon 30 the shoulder 18 which holds it positively against accidental removal.

The device is of that character wherein one field of use is in connection with medicine of an oily nature contained in the bottle or receptacle 35 13. Normally the device as a whole forms a closure for the receptacle 13 as the flange 23 is in sealing engagement with the upper edge of the neck. However with the cap 12 unscrewed or detached the bulb 22 may be compressed while 40 the tube 11 is immersed in the medicine, to draw a quantity into the tube. By operating the dropper and bulb in an obvious manner the medicine may be applied drop by drop to the nose, throat or other part desired.

45 Minor changes may be resorted to provided they fall within the spirit and scope of the invention. For example, the groove 19 may be enlarged either in diameter or in width as compared with the diameter and thickness of the 50 flange 23 without destroying the utility of the device, so long as the diameter of the flange remains substantially larger than the diameter of the constricted portion of the cap below the wall 18. The bulb and its attached dropper can be 55

kept centered in the cap either by making the flange 23 fit snugly in the groove 19, or by having the exterior diameter of the bulb 22 approach in size the internal diameter of the central cap opening 17.

5. I claim as my invention:

1. In combination, a closure cap having a top wall provided with an opening, a wall spaced below said first wall to provide a groove, an elastic bulb extending through said opening and an elastic flange at the base of said bulb occupying said groove, said flange being of greater diameter than the entrance to said groove so as to be held thereby against accidental separation, said flange having a portion extending inwardly at the entrance of said bulb, and a dropper gripped by said flange throughout the thickness of the latter.

10. 2. In combination, a closure cap having a top wall provided with an opening, a wall spaced below said first wall to provide a groove, an elastic bulb extending through said opening and an elastic flange at the base of said bulb occupying said groove, said flange being of greater diameter than the entrance to said groove so that the flange contracts sufficiently as it enters said groove to snap into said groove, said flange having a portion extending inwardly at the entrance to the bulb, and a dropper tube having an annular groove occupied by the extension of said flange.

15. 3. In combination, a closure cap having a wall provided with an opening and adapted to be gripped at its margin, said cap having a portion coacting with said wall to form an inwardly opening endless groove below the wall, an elastic body having a bulb extending through said opening and a flange at the base of said bulb having a portion occupying said groove, said flange being of greater diameter than the entrance to said

groove so as to prevent the removal of said portion of the flange from said groove without deforming the flange, a bottle engaging part depending from said portion of said cap at a location inwardly of the margin of said wall and a 5 dropper carried by said flange.

4. In a device of the class described, in combination, a cap having a top wall provided with a central opening, a marginal gripping wall depending from said top wall, an inwardly extending wall at the base of the marginal gripping wall, said walls providing an interior groove, a portion of less diameter than said gripping wall depending from the inner edge of the inwardly extending wall and adapted to seat on a bottle neck, an 10 elastic member comprising a bulb protruding through said cap opening and a flange occupying said groove, and a tube having one end connected with said bulb and its other end depending therefrom, said flange having a diameter greater than 15 the interior diameter of said portion, whereby said cap and elastic member are positively held against accidental separation and said flange may serve as a bottle seal.

5. In combination, a closure cap having a top 25 wall provided with an opening, a wall spaced below said first wall to provide a groove, an elastic bulb extending through said opening and an elastic flange at the base of said bulb occupying said groove, said flange being of greater diameter than the entrance to said groove so as to be held thereby against accidental separation, and a dropper tube carried by said elastic flange adjacent the junction of the bulb and flange, whereby the bulb 30 and cap are positively locked together forming 35 with the dropper a unitary structure removable from an engaged bottle by removal of the cap.

DAVID A. WOODCOCK.
